UNITED STATES PATENT OFFICE.

WARREN H. TAYLOR, OF STAMFORD, CONNECTICUT, ASSIGNOR TO THE
YALE & TOWNE MANUFACTURING COMPANY, OF SAME PLACE.

DESIGN FOR A LATCH-OPERATING LEVER.

SPECIFICATION forming part of Design No. 29,385, dated September 20, 1898.

Application filed August 24, 1898. Serial No. 689,439. Term of patent 7 years.

To all whom it may concern:

Be it known that I, WARREN H. TAYLOR, a citizen of the United States, and a resident of Stamford, in the county of Fairfield and State of Connecticut, have invented and produced a new and original Design for a Latch-Operating Lever, of which the following is a specification, reference being had to the accompanying drawings, forming a part thereof.

Figure I is a perspective view showing my new design for a latch-operating lever, looking at one side thereof. Fig. II is a top view, looking at the opposite side thereof.

As shown in the drawings, the leading or material features of my design consist in a flat inner portion having a blunt projection at one side, an inner angular portion having a step and inturned projection at one edge, a tailpiece in line with the lever, and a rec-

tangular block on the face of the angular portion.

The lever is formed with an inner flat arm from one edge of which projects a blunt tooth and with an outer angular portion. A short ²⁵ tailpiece extends from the angular portion in line with the lever. On one side of the angular portion is a step, and between the step and the arm is an inturned projection. From the face of the angular portion projects ³⁰ an angular block.

Having thus described my invention, the following is what I claim as new therein and desire to secure by Letters Patent:

The design for a latch-operating lever, substantially as shown and described.

WARREN H. TAYLOR.
